UNITED STATES PATENT OFFICE.

GEORGE A. COTÉ, OF MONTREAL, QUEBEC, CANADA.

SINK-STOPPER.

1,081,434.

Specification of Letters Patent.

Patented Dec. 16, 1913.

Application filed October 18, 1913. Serial No. 795,898.

To all whom it may concern:

Be it known that I, GEORGE A. COTÉ, of the city of Montreal, in the Province of Quebec, Dominion of Canada, a subject of the King of Great Britain, have invented 5 certain new and useful Improvements in Sink-Stoppers; and I do hereby declare that the following is a full, clear, and exact description thereof.

10 This invention relates particularly to means for closing the discharge from kitchen sinks which are not usually provided with stoppers; and it has for its object to enable the water to be held temporarily in the sink for washing purposes.

15 My improved device consists of an india rubber device of substantially inverted saucer form with exterior and interior bosses and the edge of its periphery extended to 20 form a flat foot, the bosses having the shank of a hook inserted therein, while one side of the device has a small external boss to indicate the side of the hook at which the opening is located. For full comprehension, 25 however, of my invention reference must be had to the accompanying drawings forming a part of this specification, in which similar reference characters indicate the same parts, and wherein:

30 Figure 1 is a transverse vertical sectional view of my improved sink stopper before being set in place; Fig. 2 is a similar view set in place; and Fig. 3 is also a similar view illustrating the manner of removing the 35 stopper; and Fig. 4 is a plan view partly broken away.

An india-rubber section of inverted saucer form is indicated at *b*. It is formed 40 with an exterior knob *c* to serve as a thumb-hold located centrally of the device and having in juxtaposition therewith an interior boss *d* with rounded end *e* extending to within close proximity of the level of the rim. The hook *f* having a long shank *g* 45 with barbs *h* and retaining disks *h'* is rigidly secured thereto, located in the boss and knob with the hook end pointed and projecting to the same plane as the rim of the device before the latter is set in place. 50 The body of the device is relatively thick in the middle and tapered in cross-section to the rim which is formed to extend outwardly at a comparatively sharp angle and present a flat annular foot *k* such foot being 55 demarcated by a circumferential incision *p*.

in order to cause it to bend outwardly when the device is pressed into place. On the same side of the device as faced by the opening in the hook I locate a small boss *m* to indicate in which direction the hook faces. 60

When setting the stopper in place it is placed over the drain connection and pressed downwardly, the effect being that the rim is bent at the line of junction between the foot and the body of the stopper, and such 65 foot is set flat on the surface of the sink surrounding the drain connection and the hook will trip over one of the bars of the grating and engage beneath it thus holding the device in place. In order to release 70 the stopper the thumb piece *c* is pressed in the direction of the arrow 1, Fig. 3, and simultaneously the small boss *m* is pressed in the direction of arrow 2 depressing the knob laterally and throwing the boss *d* in 75 the direction indicated by arrow 3 thus releasing the hook.

It is necessary to embed the shank of the hook in the rubber when in the mold in order that it may be firmly held in place, 80 and the foot must be so disposed as to rest at an acute angle to the bottom of the sink before being set.

It is preferable to make the side of the stopper having boss *m* thereon slightly 85 heavier and consequently less flexible than the opposite side in order to insure the yielding of such opposite side and the lateral movement of the boss *d* in that direction when the boss *m* is depressed. The disks *h'* 90 prevent longitudinal displacement of the hook.

What I claim is as follows:—

1. A sink stopper consisting of an india-rubber device of inverted saucer form with 95 an alined exterior knob and interior boss, the boss extending to a point in close proximity to the plane or level of the rim of the device and a hook having a shank extending upwardly into the boss and knob. 100

2. A sink stopper consisting of an india-rubber device of inverted saucer form with an alined exterior knob and interior boss, the boss extending to a point in close proximity to the plane or level of the rim of the device, and a hook having a shank extending upwardly into the boss and knob, and the rim of the said device being formed with a flat foot. 105

3. A sink stopper consisting of an india- 110

- rubber device of inverted saucer form with an alined exterior knob and interior boss, the boss extending to a point in close proximity to the plane or level of the rim of the device, a hook having a shank extending upwardly into the boss and knob, the body of such device having an exterior boss indicating the direction in which the hook faces, and the rim of the said device being formed 10 with a flat foot.
4. A sink stopper consisting of an india-rubber device of inverted saucer form with an alined exterior knob and interior boss, the boss extending to a point in close proximity to the plane or level of the rim of the device and a hook having a shank extending upwardly into the boss and knob and having 15 a retaining disk rigidly secured for pre-

venting longitudinal displacement of such hook.

5. A sink stopper consisting of an india-rubber device of inverted saucer form having a hook located at the middle of the interior thereof and the body of such device having an exterior boss indicating the direction in which the hook faces and the portion of the body contiguous to the boss of increased thickness.

In testimony whereof I have signed my name to this specification in the presence of 30 two witnesses.

GEORGE A. COTÉ.
